UNITED STATES PATENT OFFICE

PAUL HUNZIKER, OF HAMILTON BEACH, NEW YORK, ASSIGNOR TO POTDEVIN MACHINE COMPANY, OF BROOKLYN, NEW YORK, A CORPORATION OF NEW YORK

BAG MAKING MACHINE

Application filed February 6, 1930. Serial No. 426,285.

This invention relates to an improvement in bag making machinery, and has for one of its objects the provision of an improvement in the bottoming mechanism of such machines. 5 More specifically the present invention provides means whereby the accidental application of paste to the folding bar employed in forming the bottom of the bag is eliminated.

A still further object of my invention is the 10 provision of means for eliminating or reducing wear on the machine by the bottom folding chains.

In prior machines employed in the manufacture of paper bags, it is customary to employ a bottom flap folding bar driven by the 15 bottom folding chains, such bar extending across the bag tube, and in the folding operation trouble has been experienced with one of the bag bottom flaps wiping the bar, thereby 20 applying paste to the bar which becomes deposited on the outside of the succeeding tube. This of course spoils the bag and has been a source of annoyance to bag makers using these machines. The present invention 25 remedies this defect.

Furthermore in paper bag making machines of the general type to which this invention relates, the bottom flap folding chains travel over and in contact with the drum by 30 which the bag tube is fed, the chains travelling at a different linear speed than the drum, with the result that the drum becomes worn. The present invention provides a construction 35 wherein this wear is eliminated.

In the drawings accompanying this application:

Fig. 1 is an elevational view partly in section of a portion of the bottoming mechanism of a bag making machine to which my invention 40 has been shown applied;

Fig. 2 is an end elevation of the bottoming mechanism;

Fig. 3 is a detail showing the means provided by this invention for eliminating wear 45 on the drum;

Fig. 4 is a detail of the construction of Fig. 3;

Fig. 5 is a completed bag of the general 50 type made on machines of the type to which my invention relates; and

Figs. 6, 7, 8 and 9 are views showing the different stages of the bottoming operation.

Referring to the drawings in detail: 1 designates the drum of the machine by which the bag tube is advanced through the bottoming 55 mechanism. 2 designates the tucker mechanism and 3 the paste fountain, neither of which devices is a part of the present invention but shown merely for clarity of illustration.

Mounted adjacent the periphery of and at each end of the drum 1 is a stationary curved deflecting and wearing plate 4 fitting into a groove 5 formed in the periphery of the drum 1. 60

These deflecting and wearing strips 4 are provided for the purpose of properly deflecting the bottom flap folding chains 6, and for preventing wear on the surface or periphery of the drum, these chains travelling at a 70 faster linear speed than the drum 1. The chains are mounted on sprockets 7 and 8 on shafts 9 and 10, and as will be seen from Fig. 4 the rollers 11 of the chains ride in contact with the strips 4, to be deflected thereby, the 75 strips also preventing contact of the chains with the drum periphery.

By this arrangement, therefore, all wear on the drum 1 from the chains 6 is eliminated, and should the strips 4 become worn their 80 replacement is inexpensive both in labor and materials.

The chains 6 carry a bottom flat folding bar 12, this bar extending across the drum and engaging the bag tube 13, to fold over 85 the flap 14 in the operation of forming the bag bottom. Prior to the operation of the bar 12, the bag stock has been pasted as shown at 15, and in prior machines it has been found that as the bar 12 advances after 90 folding over the flap 14 it is engaged by the pasted face of the cooperating flap 14', with the result that some of the paste on this flap is applied to the bar. This paste then becomes deposited on the outside of the next 95 bag tube, which of course is very objectionable.

In accordance with the present invention I provide an intermittently operated folder plate 16 beyond the bar 12. This folder plate 100

16 is carried on a bar 17 to which it is rigidly secured, the bar being mounted in the side frames of the machine. Rigidly secured to the bar is an operating arm 19 provided at 5 its remote end with a cam follower 20 adapted to engage a driven cam 21.

The cam 21 is mounted on a shaft 22 carrying a sprocket 23. This sprocket carries a chain 24 passing over a sprocket 25 which 10 is mounted on the shaft 9 carrying sprocket 7 above referred to.

The bottoming chains 6 are driven through a gear 26 on the shaft 27 of drum 1, this gear meshing with gear 28 in turn meshing with 15 intermediate gear 29 in mesh with a gear 30 on the shaft 10 which carries the sprocket 8. This drive for the bottoming chains also supplies a drive for the cam shaft 22 through chain 24 and sprockets 23 and 25.

20 With the machine in operation, therefore, the cam 21 will rock the arm 19 and effect a corresponding rocking motion of the folder plate 16.

From an inspection of Figs. 6 to 9, it will 25 be seen that in operation the folder bar 12 and follower folder 35 as they are driven in the direction of the arrows on Fig. 1 will fold over the flap 14 and hold it in the position shown in Figs. 7 and 8, but that the flap 14' 30 is not folded over until the bar 12 has moved sufficiently to clear the flap, this flap 14' then being folded over by the folder plate 16 which is so timed in its operation as to delay the folding of flap 14' until the bar 12 has 35 reached the position just noted. The folder plate 16 remains in this position until the bag is rolled under roller 31 which holds the bottom in pasted position until delivered.

In Fig. 8 I have illustrated the plate or 40 folder 16 in its elevated position with the flap 14' in the process of being folded over, while in Fig. 9 the tube has advanced to where the flap 14' is almost completely folded. The finished bag is shown in Fig. 5.

45 It will be seen from the foregoing, therefore, that I have provided an apparatus in which the flap 14' is folded by an intermittently moving cam controlled folding plate 16 which is so timed in its operation as to permit bar 12 to advance sufficiently to clear 50 the pasted face of the flap 14' before the flap is folded over, thereby eliminating all possibility of the application of paste to the bar.

It will be seen also that wear on drum 1 55 by folding chains 6 has been entirely eliminated.

What I claim is:—

1. In paper bag machines, the combination of a rotatable drum, bottom folding 60 chains overlying the drum adjacent each end thereof, fixed chain deflecting means for each chain, said deflecting means lying intermediate the chains and drum.

2. In paper bag machines, the combination 65 of a rotatable drum, driven bottom folding

chains overlying the drum adjacent each end thereof, and fixed means overlying the drum and engaged by the chains for deflecting said chains, said fixed means preventing engagement of the chains with the drum. 70

3. In paper bag machines, the combination of driven folding chains, a folder bar carried thereby for folding over one flap of a bag bottom, and a cam controlled driven folder for folding over another flap of the 75 bag bottom following the folding of the first flap.

4. In paper bag machines, the combination of driven folding chains, a folder bar carried thereby for folding over one flap of a bag bottom, and an intermittently operated driven folder for folding over another flap of the 80 bag bottom following the folding of the first flap.

5. In paper bag machines, the combination of driven folding chains, a folder carried thereby for folding over one flap of a bag bottom, and an intermittently operated driven folder for folding over another flap of the bag bottom in overlapping relation to the first 85 flap, the folding of the second flap being delayed until the first folder has moved to a position beyond the end of the second flap to avoid engagement of the second flap with the 90 first folder. 95

6. In paper bag machines, the combination of driven folding chains, a folder carried thereby for folding over a flap of a bag bottom, a second driven folder for folding over another flap of the bag bottom in overlapping 100 relation to the first flap, said folders traveling in arcuate paths in opposite directions, the second folder functioning to fold its flap after the first folder has moved out of the path of the second flap. 105

7. In paper bag machines, the combination of driven folding chains, a folder carried thereby and extending across a bag tube, means for advancing the bag tube and folder at different linear speeds to effect a folding of 110 a flap of the bag bottom, a second folder for folding a second flap in the bag bottom, and means for intermittently moving said second folder into folding position, the movement of the second folder being delayed until the 115 first folder has been moved out of the path of the second flap.

This specification signed this 31 day of January, 1930.

PAUL HUNZIKER. 120
